UNITED STATES PATENT OFFICE.

CHARLES HOOPER, OF PORT NORFOLK, VIRGINIA.

DESIGN FOR A KITCHEN-CABINET.

SPECIFICATION forming part of Design No. 25,326, dated March 31, 1896.

Application filed February 19, 1896. Serial No. 579,968. Term of patent 7 years.

To all whom it may concern:

Be it known that I, CHARLES HOOPER, a citizen of the United States, residing at Port Norfolk, in the county of Norfolk, State of Virginia, have invented and produced a new and original Design for Kitchen-Cabinets, of which the following is a specification, reference being had therein to the accompanying drawing.

- 10 This design relates to kitchen-cabinets and embodies a cabinet having a flat top with sliding compartments therebeneath and compartments with rounded bottoms beneath the same.
- 15 The accompanying drawing represents a perspective view of the cabinet.
- 20 The top A is flat. The front of the cabinet beneath said top is made up of a number of panels forming the fronts of the drawers and slides, and said drawers have centrally-dis-

posed knobs or handles. The lower drawers or compartments B B have rounded bottoms and ends.

One end of the cabinet proper has projecting therefrom the projections *a*.

The leading features of my design consist of the flat top extended over the entire cabinet, the sliding drawers located beneath the top and their fronts forming panels, and the lower compartments with rounded bottoms and ends.

What I claim as new is—

The design for a kitchen-cabinet substantially as shown and described.

In testimony whereof I affix my signature in presence of two witnesses.

CHARLES HOOPER.

Witnesses:

E. H. BOND,
E. B. STOCKING.
